(57) **CLAIM**

The ornamental design for a bollard light fixture, as shown and described.

DESCRIPTION

1. Bollard light fixture

Bollard light fixture.

FIGURE 1.1 is a top perspective view of a first embodiment of the bollard light fixture.

FIGURE 1.2 is a bottom perspective view a first embodiment of the bollard light fixture.

FIGURE 1.3 is a front elevation view of a first embodiment of the bollard light fixture.

FIGURE 1.4 is a back elevation view of a first embodiment of the bollard light fixture.

FIGURE 1.5 is a right side elevation view of a first embodiment of the bollard light fixture.

FIGURE 1.6 is a left side elevation view of a first embodiment of the bollard light fixture.

FIGURE 1.7 is a top view of a first embodiment of the bollard light fixture.

FIGURE 1.8 is a bottom view of a first embodiment of the bollard light fixture.

The broken lines shown on the drawings depict portions of the bollard light fixture that form no part of the claimed designs.

1 Claim, 8 Drawing Sheets
